LAUNDRY MARKING MACHINE

William J. Keuper, Cincinnati, Ohio, assignor to
 The National Marking Machine Company, Cincinnati, Ohio, a corporation of Ohio

Application December 24, 1942, Serial No. 470,052

23 Claims. (Cl. 101—101)

My invention relates to improvements in laundry marking machines and the principal object thereof is to provide an improved machine of simple, compact and inexpensive construction, by means of which a number of identifying characters may be printed upon articles to be laundered, or other material, held upon the platen of the machine by the operator.

A further object of my invention is to provide a laundry marking machine having a platen, normally accessible at the front of the machine, upon which an operator may hold the material to be marked, and which is rockable from its normal position to a printing position adjacent selected printing type and, thereafter, moves toward the type to carry the material held thereon against said type and take an imprint therefrom.

Another object of my invention is to provide a laundry marking machine having a platen, normally accessible at the front of the machine, upon which the material to be marked is held by the operator, which platen may be rocked from normal position to a printing position and is automatically projected toward the selected type, when it reaches printing position, to carry material held on the platen against said type and take an imprint therefrom.

A further object of my invention is to provide a laundry marking machine having a platen, normally accessible at the front of the machine, on which the operator may hold the material to be marked, which platen is rockable from normal to printing position and back, together with means opposing the initial movement of the platen from normal position and effective, as the platen nears printing position, to assist and complete such movement.

Another object of my invention is to provide such a laundry marking machine with means, automatically actuated by the arrival of the platen at printing position, for projecting the platen toward the type to take an imprint therefrom upon material held upon said platen by the operator.

Another object of my invention is to provide a laundry marking machine of the type described with automatic means for repeatedly projecting the platen toward and retracting it from the selected type, so that material, held on the platen by the operator, is repeatedly pressed against the selected type to take an imprint therefrom.

Another object of my invention is to provide a laundry marking machine of the character described which has automatic means for projecting the platen toward the selected type, to carry material held thereon against said type, when the platen arrives in printing position, and in which safety control means are provided in the platen handles, so that the platen-projecting mechanism cannot work, unless said safety control means are

engaged and operated by the hands of the operator, thus insuring that his hands will not be caught between the platen and the type.

A further object of my invention is to provide 5 a laundry marking machine having a platen, upon which the operator may hold the material to be marked, and rockable from a normal position to a printing position, together with fluid pressure means for projecting the platen toward selected type, and safety means carried by the platen for controlling the admission of fluid pressure to the platen-projecting mechanism.

Another object of my invention is to provide 10 a laundry marking machine having a platen-carrier, rockable from a normal position to a printing position, a platen, upon which the material to be marked is held by the operator, and an inking device, both carried by the rockable platen-carrier, and so arranged that the inking 15 device is moved over the selected type as the platen-carrier is rocked from normal to printing position, together with means which permit the rocking of the platen-carrier away from normal position to an inspection position, in which the inking device may be filled, adjusted, or removed.

Further objects, and objects relating to 20 details of construction and economies of operation, will definitely appear from the detailed description to follow. In one instance, I have accomplished the objects of my invention by the 25 devices and means described in the following specification. My invention is clearly defined and pointed out in the appended claims. A structure constituting a preferred embodiment of my 30 invention is illustrated in the accompanying drawings, forming a part of this specification, in which

Fig. 1 is a view in side elevation of a laundry 35 marking machine embodying my invention, parts 40 of the base, the casing, and certain of the shafts, being shown in section.

Fig. 2 is a view in side elevation, on an enlarged 45 scale, of the platen-carrier, platen and inking device, a portion of the latter being shown in section, these parts being shown in the position they occupy when the platen is projected against the selected type.

Fig. 3 is a detail, sectional view, taken on the 50 line 3—3 of Fig. 2.

Fig. 4 is a detail, sectional view, taken on the line 4—4 of Fig. 1.

Fig. 5 is a fragmentary, sectional view, taken 55 in a plane at right angles to the plane of Fig. 3, and showing the platen-carrier in printing position.

Fig. 6 is a detail, fragmentary view, in side elevation, showing the platen in printing position, but before projection toward the selected type.

Fig. 7 is a diagrammatic view illustrating the

valves and connections of the fluid pressure system for projecting the platen.

Fig. 8 is a detail, sectional view illustrating the valve mechanism 100 shown in the diagram, Fig. 7.

Fig. 9 is a detail, sectional view illustrating the valve mechanism 104 shown in the diagram, Fig. 7.

Fig. 10 is an enlarged view, in side elevation, of the platen-carrier, platen, inking device, and platen-projecting mechanism of a modified form of my invention, embodying safety control buttons in the handles of the platen.

Fig. 11 is a detail, sectional view, taken on the line 11-11, of Fig. 10.

Fig. 12 is a detail, sectional view, taken on the line 12-12, of Fig. 10, and

Fig. 13 is a sectional view through the platen, taken on the line 13-13 of Fig. 11.

In the drawings, the same reference numerals indicate the same parts throughout the several views, and the sectional views are taken looking in the direction of the arrows at the ends of the section lines.

In general, my improved laundry marking machine comprises a number of shiftable type-carriers, each carrying a plurality of printing type, means for shifting the type-carriers to bring selected type to printing position, a platen upon which an operator may hold the material to be marked, means for rocking the platen from a normal position, in front of the machine, to printing position, and means for automatically moving the platen to carry the material thereon against the faces of the selected type to take an imprint therefrom. The machine includes a platen-carrier, which is rockable from normal position to printing position, and back. This platen-carrier supports the platen, upon which the operator holds the material to be marked, and an inking device, the latter being so mounted that, as the platen-carrier moves from normal to printing position, the inking device moves over the faces of the selected type to ink the same. The movement of the rockable platen-carrier is controlled by a snap-action spring mechanism, which opposes the initial movement of the platen-carrier from normal position toward printing position, but, as the platen-carrier nears printing position, acts to assist and complete that movement. Conversely, this snap-action mechanism first opposes the movement of the platen-carrier from printing position and, then, assists and completes the movement to normal position. When the platen-carrier reaches printing position, a fluid pressure mechanism is actuated automatically, which projects the platen toward the selected type to carry the material held on the platen against the type and take an imprint therefrom. This fluid pressure mechanism is such that, while the platen-carrier remains in printing position, the platen is repeatedly projected toward and retracted from the type so as to make an imprint from the type, on the material held on the platen, by repeated hammer-like blows. Means are provided for regulating the timing of these hammer-like blows.

To facilitate inspection of the inking device, the removal or adjustment thereof, or the filling of the ink reservoir with a fresh supply of ink, suitable devices are provided which permit the operator to swing the platen-carrier forwardly from normal position, so that the inking device will be readily accessible.

A modified form of my invention includes a safety feature consisting of a plurality of depressible buttons, in the handles of the platen, operating valves which control the passage of fluid

pressure to the platen-projecting mechanism. These buttons are so located that they may be depressed by the hands of the operator, while he is holding the material to be marked on the platen, and, unless these buttons are depressed, the fluid pressure cannot pass to the platen-projecting mechanism to operate the latter and project the platen toward the type. This safety feature makes sure that the hands of the operator will be in such position that they will not be caught between the platen and the selected type in the printing operation.

Referring to the numbered parts of the drawings, my improved laundry marking machine includes a plurality of type-carriers, printed type carried thereby, and means for shifting said type-carriers to bring selected type to the printing line, one form of this mechanism being shown in Fig. 1, although various other forms of type-carriers and means for operating them may be used. The machine includes a casing 10 carrying a transverse shaft 14, on which a plurality of type-carrying wheels 11 are journaled. A plurality of printing type 12 are carried on the periphery of each of these type-carrying wheels. To each type-carrying wheel 11, there is secured a gear 13, which meshes with a corresponding toothed segment 15 journaled on a transverse shaft 16. To each of these segments, there is secured an operating lever 17, which projects through a corresponding slot 19 in casing 10 and has, at its outer end, a handle 18, by means of which the lever may be shifted within the limits of the slot 19. On the interior of casing 10, adjacent each slot 19, there is a toothed rack 21 for engagement by a detent 22, carried by the lever 17, the toothed outer end of which detent is urged toward the rack 21 by spring 23. Suitable indicia 20, corresponding to the characters on the printing type 12, are arranged adjacent to each slot 19, to facilitate the setting of levers 17 by the operator. It will be obvious that, as a lever 17 is moved along its slot 19 to a point opposite the index representing a certain character, gear 13 and type-carrying wheel 11 will be rotated to bring a corresponding type to printing position. Detents 22 and racks 21 serve to align the selected type at the printing line. A number of type carrying wheels 11, gears 13, segments 15, levers 17 and slots 19 are provided, the number of sets of these elements depending upon the number of characters in the marks which the machine is to print. For instance, I have provided eight sets of these elements to enable the machine to print an identifying mark consisting of eight characters.

Upon the base 29 of the machine, there is provided a bracket 30, in which there is mounted a stub shaft 31, extending through the bracket and secured thereto by a pin 32. The platen-carrier 60 64 is provided with a pair of spaced ears 33, journaled on the projecting ends of stub shaft 31, as shown in Figs. 3 and 4. In these ears 33, there are formed sockets 34, which receive the reduced lower ends 35 of posts 36, said reduced ends being secured in the sockets by pins 37. The posts 36 extend through and are secured to a bottom plate 38. Spaced from this bottom plate is a top plate 40 having openings which receive the reduced upper ends 39 of the posts 36, the latter being secured in the top plate 40 by the pins 41. Cylinder 42 is secured in place between the bottom plate 38 and the top plate 40, and a piston 43 works in cylinder 42. Piston 43 is mounted on the reduced portion 44 of a piston rod 46, which is slidable in a bore 51 in the top plate 40. Piston 43 is secured

to piston rod 46 by means of a nut 45, screwed on the lower end thereof. A port 47 is formed in the bottom plate 38, through which fluid pressure may be admitted to cylinder 42 below piston 43, by the connections to be described later. Piston 43 is normally forced toward the bottom plate 38 by a spring 48 housed within cylinder 42, the upper end of the spring being received in the annular recess 49, formed in the lower surface of the top plate 40, while the lower end of the spring is received in an annular recess 50, formed in the top face of piston 43. Thus, spring 48 tends to move piston 43 toward bottom plate 38, while fluid pressure admitted through port 47 tends to move said piston toward top plate 40, in opposition to spring 48.

The upper end of piston rod 46 has a threaded socket 52 formed therein, into which is screwed a stud 53, projecting downwardly from a bracket 54, which normally rests on the upper surface of top plate 40. When piston 43 is moved upwardly against the pressure of spring 48, the piston rod 46 and bracket 54 will be moved upwardly, with respect to top plate 40. Bracket 54 has a pair of spaced ears 55 received within spaced recesses 56, formed in the platen 57. The platen is guided in its movements with respect to the platen-carrier by means of studs 115, screwed into sockets 114 in platen 57, and passing through holes 116 in top plate 40, as shown in Fig. 4. Wooden handles 59 are mounted on opposite ends of platen 57, and secured thereto by a rod 58 extending longitudinally through the handles, through a bore in platen 57, and through openings formed in the spaced ears 55 of bracket 54, and nuts 60 screwed on the ends of rod 58. A platen insert 61, of resilient material, is mounted on the top surface of platen 57, in position to yieldingly press material held upon said platen insert against the faces of the selected type, in taking an impression therefrom. The cover 62 is carried by the platen and houses the platen-carrier and the platen-projecting mechanism. As shown in Fig. 2, a portion of the rear wall of the housing is bent upwardly at 63, forming a guard which prevents clothes, or other material held upon the platen, from being entangled in the machine.

The body portion of the platen-carrier 64 is also provided with a pair of sockets 65, as shown in Fig. 3, which receive the lower ends of posts 66. The upper ends of these posts are connected to bosses 67 of an inking device 68, which includes an inking roller 69, an ink reservoir 70 and a wick 71, by which ink is directed from the ink reservoir to the surface of the inking roller. The inking device 68 is so mounted on the platen-carrier, with respect to the platen 61, that, when the platen-carrier is in normal position, the inking roller 69 is slightly in front of the selected type and the platen is accessible to the operator at the front of the machine. When the platen-carrier is rocked from normal to printing position, in which the platen is opposite the selected type, the inking roller 69 rolls over the faces of the selected type, applying ink thereto, and reaches the position shown in Fig. 2.

A cross bar 74 is mounted on the posts 66, being secured thereto by pins 75, and an adjusting screw 76 passes through an opening in said cross bar and screws into a threaded socket 79 formed in the body of the platen-carrier 64. The head 77 of the adjusting screw engages the top surface of the bar 74, while a washer 78, mounted on the adjusting screw and pinned thereto, engages the lower surface of said cross bar, so that

the adjusting screw is revoluble in the cross bar but held against longitudinal movement with respect thereto. By screwing the adjusting screw into and out of the socket 79 in the platen-carrier, the inking device can be adjusted with respect thereto, to regulate the contact of inking roller 69 with the faces of the selected type. A lock nut 80, threaded on the adjusting screw and engaging the top surface of the platen-carrier 64, serves to lock the adjusting screw in its positions of adjustment.

Mounted on base 29 is a pair of spaced brackets 81. In each of these brackets, a U-shaped member 83 is journaled on a trunnion 82. A shoulder 84 on each U-shaped member 83 engages the base of the corresponding bracket 81, as shown in Fig. 2, to limit the movement of said U-shaped member, in one direction, with respect to said bracket. Each U-shaped member 83 carries a guide 86, pivotally mounted therein by means of the pivots 85. In each of these guides 86 there is slidably mounted a rod 87, the forward end of which is pivotally connected by pivot 88 to ears projecting rearwardly from the platen-carrier. The rear end of each rod 87 has an enlarged head 90 adapted to engage the rear end of the corresponding guide 86, to limit the movement of the rod with respect to said guide, in one direction. On each rod 87, there is mounted a spring 91 interposed between the front end of the guide 86 and a shoulder 92 on the rod. When the platen-carrier is in the normal position shown in Fig. 1, the springs 91 resist movement of the platen-carrier from normal toward printing position, but, as the platen-carrier is rocked about the axis of shaft 31, to carry the platen from normal to printing position, springs 91 are compressed until the axis of pivot 88 crosses the line connecting the axes of pivots 85 and shaft 31, and, thereafter, springs 91 expand and force the platen-carrier to complete its movement to the full printing position. Thus, the parts just described constitute a spring snap-action or toggle mechanism, which yieldingly opposes initial movement of the platen-carrier from printing position, but serves, as the platen-carrier nears printing position, to complete its movement to that position. When the platen-carrier is in printing position, springs 91 oppose movement thereof from that position, until the platen-carrier is rocked sufficiently to carry pivots 88 past dead center, and, thereafter, the springs move the platen-carrier to normal position. Movement of the platen-carrier toward printing position is limited by engagement of the side thereof with a valve mechanism 104, to be described later, which thus determines the printing position of the platen-carrier.

As shown in Figs. 2 and 12, each of the U-shaped members 83 is provided with shoulders 93 to be engaged by detent arms 94, projecting forwardly and upwardly from a member 94' (Fig. 12), journaled on the pivot shaft 95, which is carried by brackets 96 mounted on base 29. Springs 97, coiled around shaft 95 and each having one end secured to said shaft and the other end hooked over an adjacent detent arm 94, tend to swing said detent arms to positions where they will engage the shoulders 93, and prevent rocking of the U-shaped members 83 about their pivots 82. Member 94' has a handle 98 extending rearwardly therefrom and, by pressing down on handle 98, the detent arms 94 can be swung counter-clockwise, against the tension of springs

97, to remove them from engagement with shoulders 93. When this has been done, the U-shaped members 83 can swing clockwise about pivots 82. This permits one to swing the platen-carrier clockwise about axis 31 from the position shown in Fig. 1, so as to move the inking device 68 to a position in which it can be inspected, adjusted, filled with ink or, if need be, removed from the platen-carrier. After this has been done, the platen-carrier can be swung counter-clockwise until detent arms 94 engage shoulders 93, whereupon the U-shaped members 83 will be retained in normal position.

As shown in Fig. 1, in the normal position of the platen-carrier, the platen is accessible at the front of the machine so that the operator may place material to be marked thereon, and hold it upon the platen while grasping the handles 59. He, then, pushes rearwardly on the platen, against the pressure of springs 91, until this spring toggle mechanism acts to complete the movement of the platen-carrier to printing position. This carries the platen, and the material held thereon by the operator, opposite the faces of the selected printing type to the position shown in Fig. 6. It will be noted that the platen is spaced from the selected type, in this position. When the platen-carrier reaches printing position, automatic mechanism becomes effective to admit fluid pressure to cylinder 42, below piston 43, so as to move the platen upwardly against the pressure of spring 48, thus carrying the material held on the platen against the faces of the selected type to take an imprint therefrom.

In Fig. 7, I have shown diagrammatically the fluid pressure connections to the mechanism for projecting the platen to carry the material thereon against the selected type. A line 99, connected with a source of fluid pressure (not shown), is connected to the inlet of a normally-open three-way valve 100, which has an exhaust connection 101 to the atmosphere and an outlet pipe 102 leading to the valve 104. The valve 100 includes a spring-pressed button 103. In the normal position, pipe 99 is connected to pipe 102, so that communication is established from the source of fluid pressure to the inlet of valve 104, but, when the spring-pressed button 103 is depressed, pipe 99 is cut off from pipe 102 and the latter is connected to the exhaust passage 101 leading to the atmosphere. Except for the fact that it is a normally-open valve, whereas valve 104 is a normally-closed valve, valve 100 is of much the same construction as valve 104, and, since the latter will be described in detail, I do not deem it necessary to repeat that description for valve 100.

As shown in Fig. 7, pipe 102 is connected to the inlet of valve 104, the details of which are shown in Fig. 9. Valve 104 has an exhaust passage 105 and an outlet passage which connects to pipe 107, leading to the port 47 through which fluid pressure is admitted to cylinder 42 below the piston 43, as previously described. Valve 104 includes a spring-pressed button 106. In the normal position, with this button 106 projecting, pipe 102 is cut off from pipe 107, and the latter is connected to the exhaust passage 105. When the button 106 is depressed, pipe 102 is connected to pipe 107, and the latter is cut off from the exhaust passage to the atmosphere.

Referring to Fig. 9, the body of valve 104 includes an annular recess 117, which is connected by inlet passage 118 to pipe 102. The valve body is also provided with an annular recess 119, which

is connected by outlet passage 120 to the pipe 107. The body of valve 104 has a transverse bore 120', having an internal shoulder 122, against which one end of a sleeve 121 is seated. This sleeve is held in its position by a nut 123, screwed into the enlarged upper end of the bore. Sleeve 121 has an internal shoulder against which a washer 124 is seated. The rod 125 is slidably mounted in this washer and carries a pair of spaced pistons, 126 and 127, which work within the sleeve 121. These pistons are spaced by means of a sleeve 128 and held in position by nut 129, screwed on the lower end of rod 125. The upper end of the rod is screwed into the button 106, which is slidably mounted in a recess in nut 123, and a spring 129, interposed between the button and the washer 124, normally projects this button from the recess, as shown in Fig. 9. Ports 130 are provided in sleeve 121, in line with the annular recess 117, and similar ports 131 are provided in line with the annular recess 119. In the position of the parts shown in Fig. 9, the annular recess 117 and inlet passage 118 are cut off from the annular recess 119 and outlet passage 120 by the lower piston 126, and recess 119 and passage 120 are vented to the atmosphere through the ports 131 and the open, lower end of bore 125. When button 106 is depressed, against the pressure of spring 129, piston 126 passes below ports 131, while piston 127 still remains above ports 130. Consequently, passage 118, annular recess 117, and ports 130 are connected with ports 131, annular recess 119, and passage 120, so that communication is established between pipe 102 and pipe 107, and the latter is cut off from its connection to the atmosphere.

As shown in Figs. 2 and 5, the valve mechanism 104 is so located that, when the platen-carrier 64 moves to printing position, the side 40 thereof engages and depresses button 106, thereby establishing communication between pipe 102 and pipe 107, and cutting the latter off from its connection to atmosphere. Hence, if at this time valve 100 is open, fluid pressure is admitted from 45 the source through pipe 99, valve 100, pipe 102, valve 104, pipe 107 and port 47, to the space in cylinder 42 below piston 43, thus forcing said piston upwardly against the pressure of spring 48, and thereby projecting the platen, and the 50 material held thereon by the operator, against the selected type to take an impression therefrom on said material. It is to be noted that the fluid pressure mechanism cannot act in this way until platen-carrier 64 has been moved to 55 printing position, so that it will depress button 106.

As shown diagrammatically in Fig. 7, a branch pipe 108 leads from the pipe 107 to one end of a cylinder 109. A piston 110 works in this cylinder and is connected to a piston rod 112, which projects from the opposite end of the cylinder and has a head 113 thereon, in position to engage and depress the button 103 of valve 100, when the piston has been moved by fluid pressure to one end of cylinder 109. A spring 112' is interposed between one end of the cylinder and piston 110, tending to move the piston 110 and rod 112 away from button 103. A needle valve 111 is provided in branch pipe 108, for controlling the size 60 of the aperture through which fluid pressure may be admitted to cylinder 109, thus controlling the rate of admission of fluid pressure to said cylinder. When fluid pressure is admitted through pipe 107 to cylinder 42, it is also admitted through pipe 108, to cylinder 109, and moves piston 110

and rod 112, against the pressure of spring 112', until the head 113 engages and depresses the button 103. This closes the connection between the source of fluid pressure and pipe 102, and connects pipe 102 with the atmosphere through exhaust passage 101, so that both cylinders 42 and 109 are vented to the atmosphere. As a result, spring 48 presses piston 43 downwardly, thus moving platen 61 and the material held thereon away from the selected printing type, and, at the same time, spring 112' moves piston 110 to the right (Fig. 7) to permit the button 103 again to be projected by its spring. When this happens, communication is established again between pipe 102 and the source of fluid pressure, so that piston 43 is raised again against the pressure of spring 48, to carry the platen and the material held thereon against the selected type to take an impression therefrom, and piston 110 is moved again to the left (Fig. 7) until head 113 engages and depresses the button 103, to cut off once more the connection between pipe 102 and the source of fluid pressure. As a result, as long as the platen-carrier remains in printing position, the platen and the material held thereon will be raised repeatedly toward and withdrawn from the printing type, so that the mark is made on the material by repeated hammer-like blows of the platen. The needle valve 111 may be adjusted to control the rate at which fluid pressure enters cylinder 109 and, thus, control the timing of these repeated operations of piston 43.

From the description of the parts heretofore given, the operation of my improved laundry marking machine should be very readily understood. In the normal position of the platen-carrier, the platen insert 61 is accessible to the operator, at the front of the machine. The operator stretches the garment, or other material to be marked, over the upper face of this platen insert, holding it there while he grasps the handles 59. Pressing rearwardly on these handles, he, then, rocks the platen-carrier from normal to printing position, overcoming the pressure of springs 91 until the parts have passed dead center, when the springs complete the movement of the platen-carrier to printing position, and hold it there. During this rocking of the platen-carrier, the roller 68 of the inking device has rolled over the faces of the selected type, applying ink thereto, and the platen-carrier has moved until the platen insert 61 is opposite the selected type, as shown in Fig. 6. As soon as the platen-carrier reaches printing position, it depresses button 106, admitting fluid pressure to cylinder 42 to raise piston 43 against the pressure of spring 48 and, thus, carry the material held on platen insert 61 against the face of the selected and inked type, to take an impression on said material therefrom. As has been described, the platen will be repeatedly raised and lowered while the platen-carrier remains in printing position holding button 106 of valve 104 depressed. When the marking is completed, the operator pulls forwardly on handles 59, overcoming the pressure of springs 91 until dead center has been passed, when said springs complete the movement of the platen-carrier to normal position, and the material marked can then be removed and fresh material placed and held on the platen by the operator.

In Figs. 10 to 13, inclusive, I have shown a modified form of my invention, which differs from that shown in Figs. 1 to 9, inclusive, only in that it is provided with a safety feature which pre-

vents the operation of the platen-projecting mechanism when the operator's hands are between the platen and the printing type. In this modified form, the bottom plate 38 is not provided with the port 47, through which fluid pressure is admitted to cylinder 42, but does have a concave recess 148 in its upper surface, substantially at the point where the port 47 was located in the other form of the device. The piston rod 44 has a passage 147 extending longitudinally thereof and communicating with a longitudinal passage 147' formed in bracket 54 and the threaded stud 53. In this modified form of my invention, the platen 134 is provided with integral handle portions 135 and 136, respectively, and it is secured to bracket 54 by screws 134'. As in the preferred form, the platen carries the rectangular platen insert 61, of resilient material, for yieldingly pressing the material to be marked against the selected type in taking an impression therefrom.

One of the studs 115 has a passage 133 extending longitudinally thereof, which communicates with a chamber 137 formed in platen 134. As shown in Fig. 13, chamber 137 is connected by passage 138 with an annular recess 139 in the handle 136 and the adjacent annular recess 140, in said handle 136, is connected by a passage 141, extending longitudinally of the platen, with an annular recess 142 in the handle 135. An adjacent annular recess 143, in said handle 135, is connected by a passage 144 to a central chamber 145, which connects with the passage 146, in line with and communicating with the said passage 147' in the bracket 54 and stud 53. A valve mechanism, similar in construction to valve 104 shown in Fig. 9, is mounted in each of the handle portions of the platen, and each valve mechanism includes a spring-pressed button 106, normally projected outwardly by a spring 129. These valves are normally closed, since the ports 130 and 131 are sealed off from each other by the innermost of the two pistons of the valve. Accordingly, the annular recesses 139 and 140 of the handle 136 are cut off from each other, when the valve is in its normal closed position, and, likewise, communication is cut off between the annular recesses 142 and 143 of the handle 135, when the button 106 of the valve in that handle is in its normal position. But, when both buttons 106 are depressed, against the pressure of their springs 129, the ports 130 and 131 are in communication with each other and, consequently, annular recess 139 is connected to annular recess 140, and annular recess 143 is connected to annular recess 142.

The bores in which these valves are mounted are connected to atmosphere through the exhaust passages 149 and 150, formed in the platen.

In this modified form of my invention, pipe 107, instead of being connected to port 47, is connected by pipe 132 to the lower end of the passage 133 in stud 115. Accordingly, when the platen-carrier is in printing position so that the valve 104 is open, fluid pressure may pass through pipe 132 and passage 133 into chamber 137 and, thence, through passage 138 to annular recess 139 in the handle 136. If button 106 is pressed inwardly, recess 139 will be connected to annular recess 140, which in turn is connected by passage 141 to annular recess 142 in the handle 135. If button 106 of the corresponding valve is pressed inwardly, annular recess 142 will be connected to annular recess 143, which in turn is connected through passage 144, chamber 145 and passages

146, 147' and 147 to the interior of cylinder 42, below the piston 43. Accordingly, if valve 104 is open because the platen-carrier is in printing position depressing the button 106 thereof, and if both of the valves in the platen handles are open because of the buttons 106 thereof having been pressed inwardly, fluid pressure may flow from the source through pipe 107, pipe 132, and the passages heretofore traced in the platen, to the space in cylinder 42 below piston 43, thus lifting said piston against the pressure of spring 48, to move the platen 134 and platen insert 61 toward the selected type, pressing the material held on the platen against said type to take an imprint therefrom. When the valve buttons 106 are in their normal projected positions, as shown in Figs. 11 and 13, the space below the piston 43 will be vented to the atmosphere through passages 147, 147', 146, chamber 145, passage 144, annular recess 143 and passage 150, and the annular recess 140 will be vented through the passage 149. As long as the platen-carrier remains in printing position, and the valves in the platen handles are held open by depression of buttons 106, the platen will be moved repeatedly toward and from the selected type, so as to make an imprint upon the material held thereon by repeated hammer-like blows of the platen.

The operation of the modified form of my invention should be quite apparent from the description given heretofore. In the modified form, the operator places the material to be marked over the platen insert 61, holding it there while grasping the platen by the handles 135 and 136, and the buttons 106 of the handle valves are so located that the operator may depress them by the palms of his hands, while holding the material in place over the platen insert. Since it is necessary to depress the buttons 106, to cause the platen to be projected toward the type, the operator must keep his hands in such position that the palms will hold the buttons depressed and this requires that the hands be so located on the platen that they cannot get caught between the platen and the type, when the platen is moved toward the type.

When the modified form of my invention, including the handle control valves, is used, the normally-open valve 100, the cylinder 109 and the branch pipe 108 may be eliminated and the pipe 99 leading to the source of fluid pressure connected directly to the inlet of valve 104. With this arrangement, repeated hammer-like blows of the platen against the type may be obtained by alternately depressing and releasing the control button 106 of the valve in handle 135, when the platen-carrier is in printing position.

I am aware that the laundry marking machine disclosed herein is susceptible of considerable variation without departing from the spirit of my invention and, therefore, I claim my invention broadly, as indicated by the appended claims.

What I claim is:

1. In a laundry marking machine including a type assembly adapted to locate type at printing position, the combination of a platen-carrier, means for rocking said platen-carrier from a normal to a printing position, a cylinder mounted on said platen-carrier, a piston working in said cylinder, a platen secured to said piston, and means, automatically actuated by movement of the platen-carrier to printing position, for admitting fluid pressure to said cylinder behind said piston to move the platen toward the selected type.

2. In a laundry marking machine including a type assembly adapted to locate type at printing position, the combination of a platen-carrier, means for rocking said platen-carrier from a normal to a printing position, a cylinder mounted on said platen-carrier, a piston working in said cylinder, a platen secured to said piston, a valve controlling the admission of fluid pressure to said cylinder behind said piston to move the platen toward the selected type, and means for actuating said valve by movement of the platen-carrier to printing position.
3. In a laundry marking machine including a type assembly adapted to locate type at printing position, the combination of a platen-carrier movable from a normal, material-receiving position to a printing position, a cylinder mounted on said platen-carrier, a piston working in said cylinder, a platen secured to said piston and on which material to be marked may be placed when the platen-carrier is in normal position, and means for admitting fluid pressure to said cylinder behind said piston to move the platen with respect to the platen-carrier.
4. In a laundry marking machine including a type assembly adapted to locate type at printing position, the combination of a platen-carrier movable from a normal, material-receiving position to a printing position, a cylinder mounted on said platen-carrier, a piston working in said cylinder, a platen secured to said piston and on which material to be marked may be placed when the platen-carrier is in normal position, and means, automatically actuated by movement of the platen-carrier to printing position, for admitting fluid pressure to said cylinder behind said piston to move the platen with respect to the platen-carrier.
5. In a laundry marking machine including a type assembly adapted to locate type at printing position, the combination of a platen-carrier movable from a normal, material-receiving position to a printing position, a platen carried thereby on which material to be marked may be placed, and means for repeatedly moving said platen to and from the selected type, while said platen-carrier remains in printing position, said moving means including a timing device for determining the frequency of repeat operation.
6. In a laundry marking machine including a type assembly adapted to locate type at printing position, the combination of a platen-carrier movable from a normal, material-receiving position to a printing position, a platen carried thereby on which material to be marked may be placed, and means, automatically actuated by movement of the platen-carrier to printing position, for repeatedly moving said platen to and from the selected type, while the platen-carrier remains in printing position, said moving means including a timing device for determining the frequency of repeat operation.
7. In a laundry marking machine including a type assembly adapted to locate type at printing position, the combination of a platen-carrier movable from a normal to a printing position, a cylinder mounted on said platen-carrier, a piston working in said cylinder, a platen secured to said piston, and means for alternately admitting fluid pressure to and exhausting it from said cylinder, while said platen-carrier remains in printing position, said pressure admitting means including a timing device for determining the frequency of repeat operation.
8. In a laundry marking machine including a

type assembly adapted to locate type at printing position, the combination of a platen-carrier movable from a normal to a printing position, a platen carried thereby on which material to be marked may be placed when the platen-carrier is in normal position, a cylinder, a piston working therein, connections between said piston and said platen, and means for alternately admitting fluid pressure to and exhausting it from said cylinder, while the platen-carrier remains in printing position, said pressure admitting means including a timing device for determining the frequency of repeat operation whereby said platen is repeatedly moved to and from the selected type.

9. In a laundry marking machine including a type assembly adapted to locate type at printing position, the combination of a platen-carrier movable from a normal to a printing position, a platen carried thereby, a cylinder, a piston working therein, connections between said platen and said piston, whereby reciprocation of the latter in said cylinder moves the platen to and from the selected type, a source of fluid pressure, a line connecting said source with said cylinder, and a normally-closed valve in said line including a spring-pressed button, said button being so located as to be depressed by a part carried by the platen-carrier upon movement of said platen carrier to printing position, to open said valve and connect said source with the cylinder.

10. In a laundry marking machine including a type assembly adapted to locate type at printing position, the combination of a platen-carrier movable from a normal to a printing position, a platen carried thereby, a cylinder, a piston working therein, connections between said platen and said piston, whereby reciprocation of the latter in said cylinder moves the platen to and from the selected type, a source of fluid pressure, a line connecting said source with said cylinder, a normally-closed valve in said line including a spring-pressed button so located as to be depressed by movement of the platen-carrier to printing position, to open said valve and connect said source with the cylinder, a normally-open valve in said line between the source and the normally-closed valve, and means, actuated by the opening of the first-named valve, to close the second-named valve and cut off the supply of fluid pressure to said cylinder.

11. In a laundry marking machine including a type assembly adapted to locate type at printing position, the combination of a platen-carrier movable from a normal to a printing position, a platen carried thereby, a cylinder, a piston working therein, connections between said platen and said piston, whereby reciprocation of the latter in said cylinder moves the platen to and from the selected type, a source of fluid pressure, a line connecting said source with said cylinder, a three-way valve in said line normally cutting off said source from said cylinder and connecting the latter to atmosphere, said valve including a spring-pressed button so located as to be depressed by movement of the platen-carrier to printing position, whereby to cut off the connection between the cylinder and atmosphere and connect said source of fluid pressure to the cylinder, a normally-open three-way valve in said line between said source and the first-named valve, normally connecting the inlet thereof to said source and cutting it off from atmosphere, and timing means, set in operation by the opening of the first-named valve, and acting to close said second-named valve at the end of a predetermined interval, whereby

to cut off said source from the inlet of the first-named valve and connect said inlet to atmosphere.

12. In a laundry marking machine including a type assembly adapted to locate type at printing position, the combination of a platen-carrier movable from a normal to a printing position, a platen carried thereby, a cylinder, a piston working therein, connections between said platen and said piston, whereby reciprocation of the latter in said cylinder moves the platen to and from the type, a source of fluid pressure, a line connecting said source with said cylinder, a normally-closed valve in said line, a normally-open valve in said line, a second cylinder, a second piston working therein, said line having a branch extending to said second cylinder from a point between the normally-closed valve and the first-named cylinder, means, actuated by movement of the platen-carrier to printing position, for opening the normally-closed valve to admit fluid pressure to both said cylinders, and means, actuated by movement of said second piston, for closing said normally-open valve to cut off both said cylinders from said source of fluid pressure and exhaust them to atmosphere.

13. In a laundry marking machine including a type assembly adapted to locate type at printing position, the combination of a platen-carrier rockable about an axis from a normal to a printing position, a platen carried thereby, on which the material to be marked may be placed when the platen-carrier is in normal position, means, effective when the platen-carrier is in printing position, for moving the platen with respect thereto to carry material thereon against the selected type, a supporting member, an abutment carried thereby, and a spring interposed between said abutment and the platen-carrier, whereby movement of the latter from normal position will compress said spring until the platen-carrier nears printing position when the spring will expand to force the platen-carrier to printing position.

14. In a laundry marking machine including a type assembly adapted to locate type at printing position, the combination of a platen-carrier rockable about an axis from a normal to a printing position, a platen carried thereby, on which the material to be marked may be placed when the platen carrier is in normal position, means, effective when the platen-carrier is in printing position, for moving the platen with respect thereto to carry material thereon against the selected type, a supporting member, a guide pivoted thereon, a rod pivotally connected to the platen-carrier and slidably in said guide, and a spring on said rod interposed between said guide and the platen-carrier, the rocking of said platen-carrier from normal to printing position causing the pivot connecting said rod and the platen-carrier to cross the line drawn from the center of the guide pivot to the axis about which the platen-carrier rocks, whereby said spring first opposes and then assists the rocking movement of the platen-carrier.

15. In a laundry marking machine including a type assembly adapted to locate type at printing position, the combination of a rockable platen-carrier, a platen carried thereby, an inking device mounted thereon, means for rocking said platen-carrier in one direction from a normal to a printing position and return, whereby said inking device is carried over the face of the selected type to ink the same, a pivotally mounted member, a link connecting said member to the platen-carrier, and a releasable detent restraining said

member from pivotal movement, whereby upon release of said detent the platen-carrier may be swung from normal position to a position in which the inking device is accessible.

16. In a laundry marking machine including a type assembly adapted to locate type at printing position, the combination of a rockable platen-carrier, a platen carried thereby, an inking device mounted thereon, means for rocking said platen-carrier in one direction from a normal to a printing position and return, whereby said inking device is carried over the face of the selected type to ink the same, a pivotally mounted member, a guide journaled thereon, a rod pivotally connected to the platen-carrier and slideable in the guide, means limiting movement of the rod in said guide in one direction, and a releasable detent restraining said member from pivotal movement, whereby upon release of said detent the platen-carrier may be swung from normal position to a position in which the inking device is accessible.

17. In a laundry marking machine including a type assembly adapted to locate type at printing position, the combination of a platen on which material to be marked may be held by the operator, fluid pressure means for moving the platen toward the selected type to take an imprint therefrom on said material, a safety control valve carried by said platen, and connections between said valve and said means whereby said valve controls the admission of fluid pressure to said means to move the platen toward the type.

18. In a laundry marking machine including a type assembly adapted to locate type at printing position, the combination of a platen on which material to be marked may be held by the operator, fluid pressure means for moving the platen toward the selected type to take an imprint therefrom on said material, a normally-closed valve carried by said platen, an operating member therefor accessible to the operator when holding material on said platen, and connections between said valve and said means whereby the opening of said valve admits fluid pressure to said means to move the platen toward the type.

19. In a laundry marking machine including a type assembly adapted to locate type at printing position, the combination of a platen on which material to be marked may be held by the operator, fluid pressure means for moving the platen toward the selected type to take an imprint therefrom on said material, a pair of normally-closed valves carried by said platen, one at each end thereof, operating members for said valves accessible to the hands of the operator when holding material on said platen, and connections between said valves and said means whereby the opening of both said valves admits fluid pressure to said means to move the platen toward the type.

20. In a laundry marking machine including a type assembly adapted to locate type at printing position, the combination of a platen on which material to be marked may be held by the operator, fluid pressure means for moving the platen toward the selected type to take an imprint therefrom on said material, said platen having an inlet passage connected with a source of fluid pressure, a transfer passage and an outlet passage connected with said fluid pressure means, a normally-closed valve carried by said platen and adapted when opened to connect said inlet pas-

sage to said transfer passage, a second normally-closed valve carried by said platen and adapted when opened to connect said transfer passage to said outlet passage, and operating members carried at the ends of said platen and adapted to open said valves, whereby pressure on both said operating members admits fluid pressure to said means to move the platen toward the selected type.

21. In a laundry marking machine including a type assembly adapted to locate type at printing position, the combination of a platen-carrier, a cylinder carried thereby, a piston working in said cylinder, a piston rod connected to said piston, a platen carried by said piston rod and having an inlet passage, a transfer passage, and an outlet passage, said piston rod having a passage therethrough connecting said outlet passage with the interior of said cylinder, means connecting said inlet passage to a source of fluid pressure, a normally-closed valve carried by the platen and adapted when open to connect said inlet passage to said transfer passage, a second normally-closed valve carried by the platen and adapted when open to connect said transfer passage and said outlet passage, and operating members at opposite ends of said platen adapted to open said valves, whereby pressure on both said operating members causes admission of fluid pressure to said cylinder.

22. In a laundry marking machine including a type assembly adapted to locate type at printing position, the combination of a platen-carrier movable from a normal to a printing position and return, a platen carried thereby on which material to be marked may be held by the operator, fluid pressure means for moving the platen toward the selected type to take an imprint therefrom on said material, said platen having an inlet passage therein, connections between a source of fluid pressure and said inlet passage including a normally-closed valve automatically opened by movement of said platen-carrier to printing position, and a pair of valves carried by said platen and controlling the flow of fluid pressure from said inlet passage to said fluid pressure means.

23. In a laundry marking machine including a type assembly adapted to locate type at printing position, the combination of a platen-carrier movable from a normal to a printing position and return, a platen carried thereby on which material to be marked may be held by the operator, said platen having an inlet passage, a transfer passage and an outlet passage, fluid pressure means connected to said outlet passage for moving the platen toward the selected type to take an imprint therefrom on said material, connections between a source of fluid pressure and said inlet passage including a normally-closed valve, automatically opened by movement of said platen-carrier to printing position, a second normally-closed valve carried by said platen and adapted when open to connect said inlet passage to said transfer passage, a third normally-closed valve carried by said platen and adapted when open to connect said transfer passage to said outlet passage, and operating members carried at the ends of said platen and adapted to open said second and third valves, whereby pressure on both said operating members, when said platen-carrier is in printing position, admits fluid pressure to said means to move the platen toward the selected type.

WILLIAM J. KEUPER.
